ICE CUBE DISPENSERS

Ole B. Lund, Havre, Mont.

Application July 2, 1956, Serial No. 595,177

2 Claims. (Cl. 249—45)

This invention relates to a coin-actuated dispenser for dispensing ice and more particularly to a dispenser for dispensing the ice in small pieces such as the popular ice cubes used in beverages. Dispensers are available at present for dispensing containers of cracked or cube ice. For use in such dispensers, however, the ice must be previously weighed and packaged in uniform sacks or cartons which are delivered by the dispenser as a complete closed package.

The principal object of this invention is to provide a piece ice dispenser which can be economically installed in the present dispenser cooler boxes, and which will continuously manufacture ice in the piece form desired and in direct proportion to the demands for ice without the necessity for prior packaging.

Another object of the invention is to provide means which upon receipt of the proper coin or coins will efficiently and accurately deliver the ice pieces, more particularly ice cubes, in bulk and in measured amounts to a receptacle or bag provided either by the customer or the lessee of the dispenser.

Other objects and advantages reside in the detail construction of the invention, which is designed for simplicity, economy and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved ice cube dispenser, illustrating it in place in a conventional cooler box, as it would appear with the near wall of the cooler box removed to reveal the interior thereof;

Fig. 2 is a top view of the dispenser of Fig. 1 as it would appear with the top of the cooler box removed to reveal the interior structure;

Fig. 3 is an enlarged side view of an ice weighing mechanism employed in the improved dispenser; and

Fig. 4 is a circuit diagram illustrating the electrical control circuits of the improved dispenser.

For convenience in description, the device will be described as pertaining to ice cubes. It could, however, be employed for dispensing ice balls, ice chips, chopped ice, or any other piece form of ice. While the device has been more particularly designed to be installed in the present dispensing storage cooler boxes, it can, of course, be enclosed and employed as a separate unit. In the drawing a conventional cooler box of the type employed in present coin-actuated ice-dispensing devices, is illustrated at 10, with the improved ice cube mechanism installed therein.

The improved ice cube mechanism makes use of any of the continuous types of ice cube or ice chip freezers presently available on the market. Such a conventional, continuous ice cube freezer is diagrammatically indicated

on the drawing at 11. The cubes discharging from the freezer 11 are received in a storage bin 12 which is substantially rectangular in plan and V-shaped in cross section with a semi-cylindrical rounded bottom. The bin

5 12 may be supported from a supporting member 13 secured to the rear wall of the cooler 10 and from an angle iron supporting frame 14 supported upon suitable supporting legs 15.

A scroll conveyor shaft 16 extends longitudinally of 10 the bin 12 axially of the rounded bottom thereof. The shaft 16 is journalled in suitable shaft journals 17 in the end walls of the bin 12 and is electrically driven in any desired manner, such as through the medium of a first electric motor 18 which transmits power to the shaft 15 16 at reduced speed through a conventional speed reducer 19.

The shaft 16 is provided with a relatively long helical scroll 20 of one hand and a similar relatively short, helical scroll 21 of opposite hand. The scrolls 20 and 21 are so inclined that when the shaft 16 rotates, ice cubes will be carried inwardly from both extremities of the bin 12 to an open space 22 between the two scrolls.

A rotatable screw-type elevating conveyor 23, enclosed 25 within a tubular conveyor housing 24, extends downwardly at an angle through the front wall of the bin 12 and terminates adjacent the bottom of the bin 12 in the open space 22 between the two scrolls 20 and 21. The top of the conveyor housing 24 is cut away within the bin so that the ice cubes delivered by the scrolls 20 and 21 may enter therein. In actual service the scrolls 20 and 21 have a diameter of 16 inches, while the screw conveyor 23 has a diameter of 4 inches.

The conveyor housing 24 extends forwardly and upwardly in the cooler box 10 and is supported at its forward extremity in a suitable angle iron frame 25 bolted or otherwise secured to the ceiling of the cooler 10 adjacent the front wall thereof. The screw conveyor 23 is driven from a second electric motor 26 through any 30 conventional speed reducer 27 and a universally jointed shaft 28. The motors and speed reducers are such as to rotate the scroll conveyor shaft 16 at approximately twelve revolutions per minute, while the screw conveyor 23 rotates at approximately 230 revolutions per minute.

40 The bottom of the upper extremity of the conveyor housing 24 is provided with a discharge opening 29 through which ice cubes are discharged into a weighing scoop 30. The weighing scoop 30 is secured to and supported between two tiltable side arms 31 which are affixed to and which extend from a rotatable scale shaft 32 mounted in suitable bearing boxes 33 in the angle iron frame. The scoop 30 is counter-balanced by means of a counterbalance weight 34 which is adjustably mounted on a counterbalance arm 35 secured to and extending 45 forwardly from the scale shaft 32. The weight 34 is adjusted on the arm 35 so that it will slightly exceed the weight of the scoop 30 so as to constantly urge the scoop upwardly. The downward swing of the arm 35 is stopped at a preset point by means of a stop screw 58 positioned in a cross bar 57 in the frame 25.

The scoop 30 is supported in the horizontal cube-receiving position of Fig. 1 by means of an elongated spring-loaded tiltable latch bar 36 which is mounted upon a pivot pin 37 extending outwardly from one of the side arms 31. The forward extremity of the latch bar 36 is constantly urged upwardly against a fixed stop clip 60 by means of a tension spring 38, the tension in which can be adjusted by means of an adjusting nut 39 threaded on an eye bolt 40 from which the spring 38 is suspended. The bolt 40 extends through a supporting ear 41 affixed to one side of the scoop 30.

The rear extremity of the latch bar 36 engages and

rests upon the upper extremity of an adjustable keeper member 42, which is pivotally mounted upon a pivot pin 43 projecting inwardly from the angle iron frame 25. The keeper member 42 is constantly urged toward the arcuate path of the latch bar 36 by means of a coiled wire spring 44. The amount of projection of the keeper member 42 into the path of the latch member 36 can be adjusted by means of a set screw 45 which is supported from the frame 25 in the path of the lower extremity of the keeper member 42.

As the ice cubes are delivered by the screw conveyor 23 through the opening 29 and into the scoop 30, the weight therein will gradually increase. This weight, acting downwardly on the pivot pin 37, will urge the forward extremity of the latch bar 36 downwardly against the resistance of the loading spring 38. The latch bar 36 will continue to tilt until the rear extremity of the latch bar 36 slips downwardly past the keeper member 42, so as to allow the entire scoop and its contents to swing downwardly to a substantially vertical position to dump the contained cubes. When the cubes are discharged, the counterweight 34 will return the scoop to its cube receiving position. As the scoop approaches the latter position, the rear extremity of the latch bar 36 engages the upper extremity of the keeper member 42 and forces it rearwardly against the action of the spring 44 until it snaps beneath the latch bar 36 to again support the scoop in the receiving position of Fig. 3 to receive a second load.

The cubes are dumped from the scoop 30 into a funnel-shaped hopper 46 formed upon the upper extremity of a delivery chute 47 which discharges through the front wall of the cooler box 10 into a cube-receiving hood 48. The bottom portion of the hood 48 is normally closed by means of a spring-hinged dump door 49 which may be opened by the customer to discharge the cubes into a suitable sack or other receptacle positioned on a sack shelf 50 as indicated in broken line at 59 in Fig. 1.

A conventional coin-actuated circuit closing device 51 is mounted on the front wall of the cooler box over the hood 48, a thermostatically-controlled electric switch 52 is mounted on the bin 12, and a mercury tilt-switch 53 is mounted on a switch arm 54 projecting from the scale shaft 32. The thermostatically-controlled switch 52 is connected in the operating circuit of the ice cube freezer 11 so that when the supply of cubes in the bin 12 falls below a predetermined point, the temperature change will cause the switch 52 to close the operating circuit to the freezer 11 so that additional cubes will be supplied to the bin 12 until the drop in temperature caused by the newly added cubes causes the thermostatically-controlled switch 52 to open and stop the freezer 11. Thus, it can be seen that the supply of cubes in the bin 12 will be substantially maintained at a predetermined level at all times.

The coin-actuated circuit closing device 51 can be incorporated in the circuits of the motors 26 and 18 in any suitable manner. One such operating circuit is shown in the diagram of Fig. 4 in which a solenoid-operated motor control is incorporated having a motor starting coil 56 and a motor stopping coil 55. The coils 55 and 56 actuate a switch armature 61 positioned in circuit with the current supply to the two motors 18 and 26. The tilt switch 53 is placed in circuit with the motor stopping coil 55 and the coin-actuated device is placed in circuit with the motor starting coil 56.

Let us assume that the bin 12 contains a supply of ice cubes and that the proper coins are deposited in the coin-actuated device 51. This will close an electric circuit to the starting coil 56 so that the armature 61 will close the operating circuits to the motors 18 and 26. The 70

scrolls 20 and 21 will immediately begin to pile ice cubes over the intake extremity of the screw conveyor 23 and the latter will operate to elevate the cubes and discharge them through the discharge opening 29 into the scoop 30. When sufficient cubes have been accumulated in the scoop to equal a predetermined weight, the latch bar 36 will snap past the keeper 42 and the scoop will dump the accumulated cubes into the hopper 46, which will deliver them through the chute 47 into the hood 48 for the use of the customer.

The dumping movement of the scoop 30 causes the tilt switch 53 to close a circuit to the motor stopping coil 55 to open the circuits to the motors 18 and 26 to prevent cubes from being delivered past the tilted scoop and to return the motor controls to the normal coin-receiving position.

While a specific form of the improvement has been described and illustrated herein, it is desired to be understood that the same may be varied within the scope of the appended claims, without departing from the spirit of the invention.

Having thus described the invention, what is claimed and desired secured by Letters Patent is:

1. In a coin-actuated ice cube dispensing device, means for delivering a preset weight of ice cubes comprising: a supporting frame; a horizontally positioned shaft rotatably mounted in said frame; an ice-cube-receiving scoop eccentrically mounted on said shaft; a latch bar pivotally mounted on said scoop; means on said scoop for limiting the upward movement of the first extremity of said latch bar; spring means resisting the upward movement of the second extremity of said latch bar; a keeper member supported from said frame below and in the path of said second extremity and acting to normally support said scoop in a horizontal cube-receiving position until the weight in said scoop is sufficient to tilt said latch bar against the bias of said spring so as to allow the second extremity to pass said keeper member and allow said scoop to swing downwardly to a dumping position; means for returning said scoop to the cube-receiving position, said keeper member being pivotally supported in a substantially vertical position, with the latch bar resting upon its upper extremity; and means for varying the pivotal position of said keeper member so as to adjust the degree of engagement of said latch bar therewith.

2. Means for delivering a preset weight of ice cubes as described in claim 1 in which the means for varying the pivotal position of said keeper member comprises a set screw positioned to engage the lower extremity of said keeper member so that rotation of said screw will vary the position of the upper extremity of said keeper member.
